L. E. LINDGARD

Des. 158,773

GAME BOARD

Filed Sept. 7, 1948

UNITED STATES PATENT OFFICE

158,773

GAME BOARD

Leslie E. Lindgard, Seattle, Wash.

Application September 7, 1948, Serial No. 148,491

Term of patent 14 years

(Cl. D34—5)

To all whom it may concern:

Be it known that Leslie E. Lindgard, a citizen of the United States, residing at Seattle, Washington, has invented a new, original, and ornamental Design for a Game Board, of which the following is a specification, reference being had to the accompanying drawing, forming a part thereof, in which

Figure 1 is a top plan view of a game board, showing my new design.

Figure 2 is a side elevational view of the same.

The cross hatching is to indicate contrasting color.

I claim:

The ornamental design for a game board, as shown and described.

LESLIE E. LINDGARD.
